UNITED STATES PATENT OFFICE.

HOWARD R. SARGENT, OF SCHENECTADY, NEW YORK, ASSIGNOR TO GENERAL ELECTRIC COMPANY, A CORPORATION OF NEW YORK.

CEILING-SWITCH.

SPECIFICATION forming part of Letters Patent No. 730,573, dated June 9, 1903.

Application filed September 20, 1901. Serial No. 75,735. (No model.)

To all whom it may concern:

Be it known that I, HOWARD R. SARGENT, a citizen of the United States, residing at Schenectady, county of Schenectady, State of New York, have invented certain new and useful 5 Improvements in Ceiling-Switches, (Case No. 2,064,) of which the following is a specification.

This invention relates to switches for controlling electric circuits; and its object is to provide a switch of simple construction which can be readily operated, both to open and close it, by a pull on a single cord or other connection. The device is especially intended for locations not easily accessible where the switch must be capable of control from a greater or less distance—such, for instance, as the ceiling of a room. I have therefore designated my invention as a "ceiling-switch" and will describe it as such, though it will be evident that it is capable of use in any location not readily accessible by an attendant.

Many switches have been made which are operated by pulling one of two cords, wires, or rods, and closed by pulling the other. It has also been proposed to open and close a switch by pulling a single cord, but by means of rather complicated and expensive mechanism.

My invention aims to produce a single-operating-cord switch with simple and inexpensive parts.

It consists in a switch-blade, a latch to engage with and hold said switch-blade closed, a spring to open the switch, and a cord, wire, or the like to operate the switch-blade. The switch is closed by pulling on the cord until the latch catches and locks the blade. In this position a quick jerk on the cord will throw out the latch and let the spring pull the blade open.

In the accompanying drawings, Figure 1 is a bottom plan view of a ceiling-switch embodying my invention. Fig. 2 is a side elevation thereof, partly in section. Fig. 3 is an end view. Fig. 4 is an end view of the latch and terminal, partly in section and on a larger scale.

The working parts of the switch are mount-

ed on a base-plate A, of porcelain or other insulating material, provided with holes a for the attaching-screws. A switch-blade B is pivoted to the base-plate at one end and provided with a spring for throwing it open 55 against a stop a' . I prefer to construct and arrange the spring as shown in the drawings, in which a helical spring C is placed concentric with the pivot of the blade, having one end attached to the blade and the other end secured to the base-plate, preferably by means of a stud D, located inside the spring and having a polygonal flange d , to which the end of the spring is attached and which fits into a polygonal recess a^2 in the base-plate. A fastening-screw E enters the upper end of the stud from the upper side of the base-plate. The lower end of the stud has a centrally-projecting pin d' , on which is pivoted the blade B, which may be retained in 70 place by a washer F and split pin G. A line-terminal is in electrical connection with the stud and blade, preferably a bent strip of metal H, having one end clamped above the upper end of the stud and the other end lying on the surface of the base-plate and carrying a binding-screw h . The other line-terminal is a strip of metal I, carrying a binding-screw i and fastened by screws K to lugs a^3 , depending from the face of the base-plate 75 A. Between the terminal and the lugs is clamped a contact-clip L, composed, preferably, of a double strip of sheet metal, the free ends l being separated to receive the switch-blade and the bend being opened out 80 to form a bearing for a pin M, on which is hinged a latch N. The latch has a downwardly-projecting hook u , lying in a slot l' in the upper arm of the contact-clip L and having a beveled edge on the side toward the entering switch-blade. The tip of the hook enters a hole l^2 in the lower arm of the clip. The latch is somewhat heavy and turns freely on its hinge-pin, resting normally with its hook entering the hole l^2 , as shown in Fig. 4. In 95 the blade B is a hole b , adapted to engage with the hook when the switch is closed. A cord P or other suitable operating connection is attached to the switch-blade and carried through a hole a^4 in a lug a^5 on the 100

base-plate. The hole is smooth and preferably flaring at each end to prevent wear on the cord.

- The operation is as follows: To close the switch, the attendant gives a steady pull on the cord, which swings the blade into the clip, its edge striking the beveled edge of the hook and lifting the latch. When the hole *b* comes under the hook, the latch drops by 10 gravity and locks the blade. To open the switch, the attendant gives a sharp jerk on the cord, which pulls the blade still farther into the clip; but in so doing the edge of the hole *b* presses against the beveled edge of the hook and throws the latch upward. The blade, being free to swing open under the tension of the spring, at once flies out of the clip before the inertia of the latch permits it to drop again.
- 20 It thus appears that this simple mechanism enables the switch to be opened and closed by pulling a single cord. Hence it is peculiarly well adapted for service in places out of ordinary reach.
- 25 What I claim as new, and desire to secure by Letters Patent of the United States, is—
1. A switch having a spring-actuated blade, a device for automatically locking said blade when closed and automatically releasing it when said blade is given a sudden further closing movement.
  2. A switch having a spring-actuated blade, and a gravity-lock for holding said blade closed and for releasing it on a sudden further closing movement.
  3. A switch having a spring-actuated blade, and a latch having a hook to engage with said blade when closed and be disengaged from said blade by a sudden further closing movement thereof.
  4. A switch having a spring-actuated blade,

a single cord arranged to put a tension on said spring in closing said blade, and means whereby a pull on said cord in any direction will release the blade and permit said spring to open it.

5. A switch having a spring-actuated blade, a cord for closing said blade, and a latch to lock said blade closed and having weight enough to cause its inertia to prevent it from falling instantly when thrown up by a sudden further closing movement of the blades.

6. A switch having a spring-opened blade, a cord for closing said blade, and a gravity-latch having a hook provided with a beveled edge which is engaged by said blade when closed and adapted to be released by a movement of said blade.

7. A switch having a blade provided with a hole, a gravity-latch having a beveled hook to enter said hole, a spring to open the blade, and a cord for closing said blade and also adapted to impart a further closing movement thereto causing it to disengage itself from the latch.

8. In a switch, a switch-blade, a pivot-stud therefor having a polygonal portion, a base-plate having a polygonal socket for said stud, and a spring attached to said stud and said blade.

9. In a switch, the combination with a base-plate having a polygonal socket, of a pivot-stud having a polygonal portion fitting said socket, a switch-blade pivoted on said stud, and a helical spring encircling said stud and attached to said stud and blade.

In witness whereof I have hereunto set my hand this 16th day of September, 1901.

HOWARD R. SARGENT.
